SURFACE ORNAMENTATION OF WALLS.

No. 18,429.

Patented July 3, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,429, dated July 3, 1888.

Application filed March 17, 1888. Serial No. 267,379. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photograph is a face view of my design.

10 My design consists in the central elevation, A, having vertically-rounded and inwardly-curved sides B. The face of elevation A is flat. Surrounding said elevation A is a groove or channel, C. Parallel to the edges of elevation A are elongated elevations D D', E E',

F F', and G G', and between said elevations D E F G and D' E' F' G' are channels H I J K. At each corner of the design are four small quadrangular elevations, as M N O P, between which appear channels Q R and S T. 2c The sides of elevations A D D' E E' F F' G G' M N O P are beveled or inclined.

I claim—

The design for surface ornamentation of walls, &c., substantially as herein shown and 25 described.

FREDERICK KOSKUL.
